WELL CLEANING DEVICE

James J. Santiago, Los Angeles, Calif., assignor
to John Grant, Los Angeles, Calif.

Application January 26, 1935, Serial No. 3,584

16 Claims. (Cl. 166—19)

This invention has to do generally with well cleaning devices and is more particularly concerned with such devices wherein there is provided a low-pressure-holding or charge-receiving 5 chamber with a normally closed inlet adapted to be opened at predetermined points in the well whereby the well fluid, under relatively high pressure, charges that chamber with sand or other foreign matter adjacent the inlet, or sets 10 up such fluid-movement as to dislodge foreign matter which may be offering obstruction to free passage of fluid through fissures in the formation or perforations in the well casing.

While the invention is here described in connection with a device having a single-charge, 15 low-pressure chamber adapted to be emptied after each charging and after the tool has been lifted from the well, it will be understood the illustrated inlet valve for said chamber and the 20 valve-control mechanism may be applied with advantage to the inlet of any type of low pressure chamber, irrespective of the manner in which the charged chamber is subsequently emptied and prepared for re-charge, and therefore the showing 25 of the invention as embodied in connection with a particular type of chamber is not to be considered as limitative on such broader aspects of the invention.

In this connection it is to be noted that in dislodging foreign matter from casing perforations 30 or otherwise promoting fluid flow by setting up fluid movement through the charging of the receiving chamber, (as distinguished from "bailing") the matter so dislodged is ordinarily, but 35 not necessarily, forced into the charge receiving chamber and subsequently disposed of along with the fluid charge.

The device will here be described as utilized in the cleaning of casing perforations, to which use 40 it is particularly well adapted, but this particularized description is not to be considered as in any way limitative on the adaptability on the device for other cleaning operations.

Conditions under which it is desirable or necessary 45 to perform well cleaning operations are so well known to workers in the art that it will be unnecessary here to detail them.

It is well recognized, however, that cleaning devices of the general nature set forth above must 50 have certain characteristics, not easy of attainment, in order that they may be capable of performing efficiently and surely the services required. For instance, it is highly important that the inlet to the low pressure chamber be kept 55 tightly closed until the cleaner has reached the predetermined zone of operation and yet, in spite of that tight closure and in spite of the usually high fluid pressure in that zone, the inlet must be capable of practically instantaneous 60 full-opening, under the control of the op-

erator, after reaching that zone. Further, the control mechanism must not only be sure and fast in operation, but, to be fully efficient, must be of a nature which does not interfere with the rapid lowering or raising of the device to and from the zone of operation. Further, it must present little or no danger of accidental valve-tripping. 5

Therefore it is among the general objects of the invention to provide a cleaner which shall have 10 the above desirable features, as well as others which may be pointed out to better advantage in connection with the detailed description to follow.

It may here be pointed out, however, that the present invention contemplates, as a preference, 15 a downwardly opening inlet valve which is inherently balanced, that is, its oppositely disposed end faces are of substantially equal effective cross-sectional areas and are exposed to the well pressure, the pressure on the top face therefor 20 having the effect of substantially balancing the well pressure which is otherwise effective on the lower face in a valve-closing direction. It follows that the effect of well pressure, endwise of 25 the valve, may be disregarded in effecting unseating of the valve when the zone of operation is reached, even though that pressure be relatively high.

When used in connection with the cleaning of casing perforations, it is preferable that a packer, 30 extending into engagement with the casing, be utilized for localizing the effect of the cleaner. With such a packer in use, it becomes desirable that the fluid be by-passed therearound as the cleaner is lowered to and raised from the zone of 35 operation. Since, as a matter of simplicity I preferably utilize a single duct as a part of both the inlet and by-pass passageways, it becomes desirable, when the inlet valve is open, to close the by-pass port or ports from that duct, so the localizing effect may not be minimized by fluid "short-circuiting" through said ports. 40

Therefore, as a feature of my invention, I have provided means whereby the by-pass port or ports may be closed before the inlet valve 45 is opened and then reopened after the cleaner has taken its charge. The arrangement is such that, after the zone of operation is reached, simple withdrawal movement of the cleaner accomplishes first, the closing of the by-pass, sec- 50 ond, the opening of the valve, and third, the reopening of the by-pass.

As a further feature, the packer, by virtue of its engagement with the casing, is utilized as a retarding member holding certain parts of the 55 cleaner stationary during initial withdrawal movement of the main body, thus serving to set up the particular relative movement of parts which accomplishes the specified sequential operations. 60

The invention also contemplates an improved type of slide-valve and connective means between that valve and the actuator or valve-opener.

5 In the drawings:

Fig. 1 is a side elevation of a cleaner embodying my invention;

Fig. 2 is an enlarged, longitudinally contracted section on line 2—2 of Fig. 1;

10 Fig. 3 is an enlarged fragmentary section on line 3—3 of Fig. 1;

Fig. 4 is a view similar to Fig. 3 but showing the parts in changed position;

15 Fig. 5 is an enlarged fragmentary section on line 5—5 of Fig. 1; the valve shown in Fig. 2 being here repeated for convenience of reference.

Fig. 6 is a view similar to Fig. 5 but showing the valve in open position;

20 Fig. 7 is a view similar to Fig. 6 but showing the position of parts as the cleaner is withdrawn from the well;

Fig. 8 is a section on line 8—8 of Fig. 5;

Fig. 9 is a section on line 9—9 of Fig. 6;

25 Fig. 10 is a section on line 10—10 of Fig. 5 or Fig. 7;

Fig. 11 is a section on line 11—11 of Fig. 3;

Fig. 12 is a section on line 12—12 of Fig. 6;

30 Figs. 13 and 14 are views similar to Figs. 5 and 3, respectively, but showing a modification of the invention; and

Fig. 15 is a section on line 15—15 of Fig. 14.

As has been previously stated, my cleaning device is particularly well adapted, but not limited, to the dislodgement of foreign matter from the perforations of well-casing, and therefore I have illustrated the device in Figs. 5 to 7 as positioned within such a perforated casing, or screen A having any suitable type of perforations, here conventionally indicated at B.

40 Body member C of the cleaning device is here shown as made of a plurality of sections coupled end to end, though it will be understood the showing of such sectional characteristics is not to be construed as limitative on the invention.

45 Threadably connected body or casing sections are indicated at 10, 11, 12 and 13, section 10 (Fig. 2) serving as a head or top closure for the charge-receiving or low-pressure chamber D which is annularly defined by those sections. Attachment section 14 is threadably connected to section 10 and serves as means whereby the body member may be attached to a suspension element—cable 15, for instance. Section 11, here 50 shown as longitudinally contracted, may be of any desirable length, and may, itself, be sectional. A forty foot length gives chamber D a capacity ample for most operations.

55 Head section 10 has a reduced axial bore 16 from which extends a transverse passageway 17 controlled by a spring-closed, outwardly-opening relief valve generally indicated at 18. The function of this valve is merely to relieve high pressure in the charge chamber as the tool is raised into zones of lower pressure. To facilitate unloading of chamber D, as will hereinafter be described, I preferably provide an inwardly-opening, spring-closed dump-relief valve generally indicated at 19. This valve is fully described and claimed in the copending application of W. C. Erwin, et al., on Well bailers, filed April 22, 1933, Ser. No. 667,439 wherein the valve showing is substantially identical with the instant showing. It will suffice here to state that removable screw plug 20 normally closes passage-

ways 21. When chamber D is to be unloaded, plug 20 is removed and passageway 21 is then adapted to put that chamber into communication with the atmosphere when the negative pressure therein (as created by the dumping of the fluid) is of a value allowing spring-closed valve 18 to open under atmospheric pressure.

5 Section 12 is provided with a removable dump-door 22, the construction and mounting of which are fully described in said copending application, Ser. No. 667,439, in which application the showing of the door is substantially the same as the instant showing and which application contains claims to these features. The door is opened by loosening screws 23 (which normally press the door inwardly to compress gasket 24 and thus provide a fluid-tight seal), and then sliding the door transversely to clear lugs 25 from lips 26, which latter define ways 27 (Figs. 1 and 2).

20 Section 12 is also provided with an upwardly opening check valve 28, transverse rod 29 being spaced thereabove to serve as a stop for valve-ball 30.

25 The main inlet valve for chamber D is provided in section 13a, threadably connected to section 13, and is generally indicated at 31, numerals 32 and 33 indicating the seat and closure members, respectively.

30 Member 32 is in the form of a cylinder having its upper portion projecting into chamber D, the cylinder being annularly spaced from section 13 and having one or more side inlet ports 34 opening to the chamber. The inlets are here shown as two in number and disposed diametrically opposite each other, but this showing is not to be construed as in any way limitative. Cylinder 32 is closed at its upper end 35 while its bore 36 opens downwardly to serve as a guideway for closure 33 which, in its preferred form, may be 35 typified generally as a tube or internal sleeve having outer peripheral engagement with the interior wall of cylinder 32. When in the position of Fig. 5, tube 33 closes off inlet ports 34 and preferably, though not necessarily, the tube is 40 slotted at the sides remote from said ports. The slots are indicated at 37 and it will be seen they may be considered as located at opposite sides of either inlet port. The slotting renders the tube increasingly radially expansive, at its inlet-closing portions, so internal fluid pressure directed thereagainst may be more effective in pressing the tube walls firmly against the cylinder walls, and thus insure tight closures about the inlet ports. By properly proportioning the slots (both 45 as to length and width) and properly proportioning the tube and cylinder, the valve-parts are rendered adaptable to preserve a tight seal about the inlet ports under varying internal fluid pressure, and yet the frictional resistance to their 50 relative movement, for effecting opening of the inlets, is not increased to a prohibitive degree even when that internal pressure becomes relatively great.

55 It will be seen that bore 38a of tube 33 serves as a passageway through the closure whereby well fluid is admitted to the upper end of the cylinder. Since the upper and lower faces of the tube, as exposed to fluid in the cylinder, are of substantially equal effective cross-sectional areas, the 60 tube is balanced as far as fluid pressure directed against its ends is concerned, and therefore the well pressure may be disregarded as far as its effect endwise of the closure is concerned. Accordingly, the means effective to shift the valve 75

from closed to open position does not have to offset any endwise directed fluid pressure, and may be accordingly simplified, to obvious advantage.

5 It will further be noted that the slotting of tube 33 divides that member into what may be considered oppositely disposed closure-blades 38 of arcuate cross-section (Fig. 8) and these blades may be considered as individually balanced as 10 far as the effect of fluid pressure directed against their ends is concerned.

For effecting the opening of valve 31 I provide a member 40 mounted for movement longitudinally of the body and engageable with well casing A, plus an operative connection between that member and closure 33 whereby movement of one with relation to the body sets up movement of the other. Since I have chosen here to show the invention as particularly applied to a device for 20 cleaning casing-perforations, wherein it becomes preferable to provide a packer for localizing the cleaning effect and to provide inlet and by-pass ducts extending around the packer, I have indicated the utilization of member 40 both as a 25 packer and as the member which is operatively connected to the valve closure for moving the latter to open position. However, it will be understood that the invention, considered in its broader aspects, is limited neither to this dual use of 30 member 40 nor to the by-pass provision and control therefor, for in certain cleaning operations the packer and by-pass are unessential, as is also the elongated extension of the inlet duct below the inlet valve.

35 Therefore, the following description of particularities of the friction shoe and of the by-pass arrangement here shown, is not to be construed as limitative on the broader aspects of the invention wherein those particularities are not essential.

Threadably connected to section 13a is a tube or barrel 41 which may be considered a part or extension of body C, the bore 42 of said barrel forming an inlet duct leading to valve 31 and, 45 under certain conditions, forming a part of a by-passage, as will appear. The lower end of tube 41 is closed by nose or shoe 43 (Figs. 1, 3, and 4). Mounted for sliding movement longitudinally along barrel 41, is a sleeve 44 carrying end nuts 50 45 and 46, the extent of downward movement of the sleeve being limited by upwardly facing shoulder 47 of nose 43. Pin 48 extends diametrically across the bore of sleeve 44, being terminally mounted in said sleeve in any suitable manner 55 (Fig. 12) and through slots 49 extending longitudinally of tube 41.

Connecting rod 49' extends from pin 48 to pin 50, the latter being terminally supported by lugs 51 which depend from opposite sides of closure 33. 55 The pivotal connections between the connecting rod and pins allow such relative movement as will prevent binding of the closure within cylinder 32 should barrel 41 bend in the plane of the drawings.

55 The pin-and-slot arrangement allows, within certain limits, relative longitudinal movement of sleeve 44 and closure 33 with respect to barrel 41 and cylinder 32, respectively, but holds the sleeve and valve against rotation with respect to the barrel and cylinder so registration between certain ports therein may be assured. The upper end-walls of the slots limit the upward movement of sleeve 44 and closure 33, as indicated in Fig. 5 where valve 31 is closed; though, if the slot

be extended upwardly, engagement of nut 45 with section 13a may limit this movement.

Packer 40 may be of any suitable type, being here illustrated as one well known in the art and consisting of a collar 52 shouldered at 53 on 5 sleeve 44, an upwardly opening and radially expansive rubber or composition cup 54, and a sleeve 55 adapted to thrust the cup against collar 52. Nut 56 is threaded on sleeve 44 and serves to clamp the elements of the packer assembly in 10 fixed positions on the sleeve. Spring reenforcing wires 57 may be provided for the packer-rubber.

At the lower end of sleeve 44 is a guide or centering member 58 which consists of body portion 59 having angularly spaced and longitudinally 15 extending guide ribs 60 (Fig. 11) preferably having their lower ends tapered as at 61' (Fig. 3). The guide is clamped between nut 46 and shoulder 62' on sleeve 44.

As will appear, the intake ports opening to 20 duct 42 are provided between packer 40 and guide 58. The packer serves not only as a casing-engagement member for opening the valve, as will be later described, but also in such operations as cleaning casing-perforations, is utilized to isolate the intake ports from the well fluid within casing A above the packer and thus more or less localize the effect of fluid movement (as created by the sudden charging of chamber D) at the casing perforations adjacent said intake ports. 30 Where the casing perforations are exceedingly tightly plugged it may sometimes be desirable to localize more definitely such effect by providing a packer in place of guide 58, the two packers then serving to define ends of a zone isolated both top 35 and bottom from the main fluid column within the casing. However, such provision is not essential to ordinary operations, and therefore the showing is not complicated by such an addition, it being evident that certain features of the invention are applicable with equal advantage in 40 either situation.

The packer fills the annular space between the barrel and well casing and, when the packer is moved upwardly, the fluid column thereabove 45 tends to expand it radially into tight frictional engagement with the well casing. In lowering or raising the cleaner it is therefore desirable to bypass the well fluid around the packer, for obvious reasons. Where guide 58 is of a size or nature to 50 interfere materially with the free passage of fluid therewith and particularly where it is in the form of a packer, as mentioned above, it is also desirable to bypass the fluid around that member as the cleaner is raised or lowered. In such a case 55 it is desirable that the by-pass extend to a point below the guide. In the drawings, I have shown such a bottom by-pass port so its function and control may be described, and for the same reason, in the following description it will be assumed that such provision is desirable in connection with the illustrated embodiment of the invention in spite of the fact that the guide here shown is so designed that a bottom by-pass port is not necessary. This showing of a bottom port 60 and control therefor is not, however, to be considered as limitative on the broader aspects of the invention.

Since, in the illustrated embodiment of the invention, I utilize duct 42 both as an intake duct 70 and as part of the by-passage, it becomes desirable that the by-pass ports above and below the intake ports be closed off when the duct is used for intake purposes, so the fluid may not be drawn inwardly through the by-pass ports from outside 75

the otherwise isolated intake zone and thus minimize the localizing effect within that zone when chamber D is suddenly opened to receive a charge.

- Opening into duct 42 of barrel 41 are intake ports 61 located between members 40 and 58, bypass ports 62 and 63, (ports 62 being, in effect, at all times above member 40) and bypass ports 64 (Figs. 3 and 4) which are, in effect, located below member 58 when the valve is in the closed position of Fig. 5. Barrel 41 also has bypass ports 65 between member 40 and 58 which are not ordinarily needed, except for extra capacity, when ports 64 are provided. Sleeve 44 has intake ports 66 and bypass ports 67 between members 15 40 and 58, and is also provided with bypass ports 68 above packer 40, and bypass ports 69 which are, in effect, below member 58 (Figs. 3 and 4). Ports 68 and 69 register with annular bypass grooves 68' and 69' in packer sleeve 55 and guide-body 58, respectively, ports 68'' and 69'' opening to the grooves which assure effective port registration even though the packer sleeve or guide-body rotates about sleeve 44 in the event the looseness develops between them.
- When the cleaner is lowered into the well it is in the condition of Figs. 1, 3, 5, and 10, the engagement of packer 40 with well-casing A tending to retard downward movement of the sleeve 44 and thus holding valve 31 closed. Fluid below the cleaner is bypassed during the descent of the tool through bypass ports 64, duct 42 and bypass ports 62, 68. It will also be seen that fluid may bypass packer 40 from immediately below through ports 67, 65, duct 42 and ports 62, 68, 68' and 68''. The last mentioned bypass ordinarily will be self-sufficient when member 58 is of a nature freely to pass fluid between itself and the well casing.

As the well-pressure increases during the descent of the cleaner, there results a tendency to press blades 38 more tightly into engagement with the wall of cylinder 32 and thus increasingly resist leakage tendency. There is thus imposed greater frictional resistance to valve-unseating but since the valve and all operating parts thereof are substantially balanced as far as the endwise effect of well pressure is concerned, and that effect therefore imposes no load, it is well within the power of the unseating mechanism to overcome this single resistance factor.

- When the predetermined zone of operation is reached, the driller checks the descent of the tool and then imparts limited withdrawal or lifting movement thereto by reeling-in cable 15. Since packer 40, due to its frictional engagement with well casing A, (particularly as it is radially expanded by the fluid column above when the packer starts to move up with the body member) is held against appreciable upward movement, it sets up relative longitudinal movement between sleeve 44 and the body member. Thus, with sleeve 44 held stationary, initial upward movement of body member C and barrel 41 causes that barrel to blank bypass ports 68 and 64. During this port-closing movement, cylinder 32 is drawn upwardly over closure 33, but not to an extent to open inlet ports 34, it following that by the time said inlet ports are open no fluid may be drawn into duct 42 through bypass ports 62 and 64. By the time inlets 34 are fully open bypass ports 67 will also be fully blanked. However, considering the invention in its broader aspects, this blanking of ports 67 is not essential, since those ports lie within the zone of operation, and if fluid does flow therethrough when

inlet 34 is opened, no harm will result. In fact, ports 67 or 65 may be located so they serve both as by-pass and intake ports, but since it is sometimes desirable to localize the cleaning effect within certain parts of the operative zone, this 5 shut-off of ports 67 is illustrated to show means for concentrating the cleaning effect about intake ports 66.

When body member C has been elevated to the position of Fig. 6, (when all bypass ports are 10 closed) ports 70 in blades 38 register with inlet ports 34, and ports 61 register with ports 66 (Fig. 9) chamber D thus being opened for receiving a high-pressure-charge of well fluid through the following path: ports 66, 61, duct 15 42, bore 36, bore 38a, and ports 70, 34. It will be understood, of course, that the opening of inlet ports 34 by way of ports 70 is not limitative on the invention, for if blades 38 were unported, it would merely be necessary to draw the blades 20 down far enough to uncover inlet ports 34 to accomplish the same result. The illustrated showing is preferable as it provides an arrangement where, though the blades are relatively long to insure proper resiliency, etc., ports 70 allow the 25 opening of the inlets without requiring a long blade-stroke.

Continued upward movement of body member C and barrel 41 to the position of Figs. 7 and 4, leaves valve 31 open, but carries bypass ports 31 62 to a position above sleeve 44, brings bypass ports 63 into register with ports 68, and brings bypass ports 64 into register with ports 69 (Fig. 4). Likewise it brings ports 65 and 67 into registration. Though the latter registration is between ports individually different from those in Fig. 5, the effect is the same as though the initially registering ports were re-registered. Thus, as the cleaner is subsequently raised from the well, a bypassage is opened so the fluid column 4 in the casing does not materially interfere with the raising operation. Of course, as soon as the body member is elevated to the position of Figs. 7 and 4, the engagement of shoe 43 with nut 46 serves to raise the packer along with the body, when the latter is withdrawn for dumping, in spite of such frictional engagement as may exist between the packer and the well casing.

When inlets 34 are opened, the fluid rushing into chamber D carries with it foreign matter (which is to be "bailed") and, where the device is used as a perforation cleaner, the in-rush sets up such movement in the well fluid surrounding the tool below the packer as to dislodge "slugs" of foreign matter in the perforations of the well-casing. The slugs (which are sometimes broken up by the fluid action and sometimes are removed intact) usually, though not necessarily, are carried into chamber D along with the inrushing fluid.

Check valve 30 opens, of course, during the in-rush of fluid to chamber D, and thereafter closes to form a foot-valve to hold the charge. As the cleaner is subsequently raised, there arises a differential in the internal and external pressures imposed on the cleaner body, but relief valve 18 allows a bleeding of chamber D to reduce the higher internal pressure and thus eliminates danger of bursting and allows subsequent unloading without danger or inconvenience to the operator.

After the cleaner is fully withdrawn from the well, door 22 is opened to unload chamber D, such built-up internal pressure as remains in the chamber and generally as measured by the

strength of the relief-valve spring, giving the material an initial outward impulse. To prevent a substantial negative pressure from developing in the chamber which would otherwise prevent complete unloading, plug 20 may be removed to permit inflow of air through valve 19 to the top of chamber D.

In Figs. 13, 14, and 15 I have shown a variational embodiment of my invention to which the foregoing description of structure and operation will generally apply. Therefore, such parts of the variation as are similar to those of the previously described figures will be given the same reference numerals.

15 In the variation, section 13a is considerably elongated and has a counterbore 13b. Connecting rod 49a is here shown as a tube (its bore 49b becoming a part of duct 42) its upper end being threaded into valve-tube 33 while its lower end takes pin 48 so members 49a and 44 are held against relative movement, though both are movable longitudinally with respect to barrel 41. Compression spring 50a in counterbore 13b is interposed between the upper end of the barrel 25 and the under face 51a of closure-head 51b which latter takes the upper end of tube 49a. Tube 49a and head 51b fit loosely in barrel 41 so well-fluid has access to counterbore 13b, it following that the valve arrangement is exposed to balanced 10 fluid pressure just as in the form previously described.

Barrel 41 has diametrically opposite intake ports 61a opening into duct 42, while sleeve 44 has slots 66a which register with the ports 15 throughout relative longitudinal movement between barrel and sleeve. Preferably, slots 66a are wider than ports 61a and their side walls diverge outwardly so they may be readily washed clean of débris as the cleaner passes through 10 the well-fluid.

Since tube 49a extends above and below the packer by-pass, it is provided with ports 62a and 63a, port 63a registering with port 62 and port 62a being blanked by barrel 41 when the 5 barrel and sleeve are relatively extended, as in Fig. 13. When the barrel and sleeve are relatively shifted longitudinally, ports 62a and 63a are brought into register with ports 62 and 63, respectively.

0 Blades 38a are imported, their ends being drawn below ports 34 to open the latter upon withdrawal movement of the body, as previously described.

Spring 50a tends to urge closure 33, tube 49a, sleeve 44 and packer 40 upwardly with respect to the body member to hold the parts yieldably in the positions of Fig. 13 until withdrawal movement is imparted to the body. The spring thus acts as means for resisting opening movement 5 of the valve, without increasing the frictional drag of closure 33 on the walls of cylinder 32, to prevent premature opening of the valve by force of inertia in the event the cleaner momentarily hangs up on a casing obstruction. It also insures that the valve be kept closed during lowering of the cleaner if the packer fails to engage the casing sufficiently tightly or passes through an enlarged bore in the casing. Of course when the cleaner is pulled upwardly to open the valve (it is sometimes advantageous to give it a sharp pull) the fluid column above the packer acts to check its upward movement and to expand it radially into tighter peripheral engagement with the casing, so spring 50a is overpowered and the valve is drawn open.

While I have illustrated and described a typical embodiment of the invention, it will be understood such illustration and description are merely illustrative of and not limitative on said invention, for various changes in design, structure and arrangement may be made without departing from the spirit and scope of the appended claims. 5

I claim:

1. In a well cleaner, a body member having a low-pressure chamber and a side inlet therefor, 10 a valve seat for said inlet embodying a member having a bore into which said inlet opens, one end of the bore being closed and the other end being open to admit well fluid, a closure embodying a blade mounted in said bore for movement to and from a position closing said inlet, said blade having one face engaged with the bore defining wall and the opposite face and the top and bottom of said blade being adapted to be exposed to well-fluid and being of substantially 15 equal effective cross-sectional areas, and means for moving the closure from closing position.

2. In a well cleaner, a body member having a low-pressure chamber and a side inlet therefor, 25 a valve seat for said inlet embodying a member having a bore of arcuate cross-section into which said inlet opens, one end of the bore being closed and the other end being open to admit well fluid, a closure embodying a blade of arcuate cross-section mounted in said bore for movement to and from a position closing said inlet, said blade having one face engaged with the bore defining wall and the opposite face and the top and bottom of said blade being adapted to be exposed 30 to well-fluid and being of substantially equal effective cross-sectional areas, and means for moving the closure from closing position.

3. In a well cleaner adapted to be lowered in a well casing, a body member having a low-pressure chamber and an inlet therefor, a valve for said inlet, a packer adapted to engage the well casing, said packer being mounted on and being movable longitudinally of the body member, and an operative connection between the packer and valve whereby packer-movement longitudinally of the body member is adapted to open said valve, and means for setting up such relative movement by virtue of withdrawal movement of the cleaner. 40

4. In a well cleaner, a body member having a low-pressure chamber and an inlet port therefor, 55 said body having an inlet duct leading to said port, a valve for the inlet port, a packer on the body, there being a pair of by-pass ports in the body opening into the duct, one above and one below the packer, means for closing one of said by-pass ports, and means for opening said valve when said by-pass port is closed.

5. In a well cleaner, a body member having a low-pressure chamber and an inlet port therefor, 60 said body having an inlet duct leading to said port, a valve for the inlet port, a packer on the body, there being a pair of by-pass ports in the body opening into the duct, one above and one below the packer, and means operative successively to close one of said by-pass ports and open said valve. 65

6. In a well cleaner, a body member having a low-pressure chamber and an inlet port therefor, 70 said body having an inlet duct leading to said port, a valve for the inlet port, a packer on the body, there being a pair of by-pass ports in the body opening into the duct, one above and one below the packer, and means operative successively to close one of said by-pass ports, open said 75

valve and then re-open the last mentioned by-pass port.

7. In a well cleaner, a body member having a low-pressure chamber and an inlet port therefor, said body having an inlet duct leading to said port, a valve for the inlet port, a packer mounted on and being movable longitudinally of the body member, there being a pair of by-pass ports in the body opening into said duct, one above and one below the packer, and a movable closure for one of said by-pass ports, said closure and packer being operatively connected whereby packer-movement longitudinally of the body member moves said closure.

15 8. In a well cleaner, a body member having a low-pressure chamber and an inlet therefor, a closure embodying a member mounted for movement to and from a position closing the inlet and having its bottom adapted to be exposed to well-fluid, said closure having a passageway adapted to conduct well fluid from beneath the closure to the top thereof, said top and bottom having substantially equal effective cross-sectional areas, and means for moving the closure from inlet-closing position, said means embodying a packer movably mounted on the body, and an operative connection between the packer and closure.

9. In a well cleaner, a body member having a low-pressure chamber, a cylinder disposed in the lower end of the chamber, said cylinder being closed at its upper end and open at its lower end for admission of well-fluid, a side port through the wall of the cylinder and in communication with the chamber, a tubular closure mounted for movement in the cylinder to and from a position closing said port, the wall of said tubular closure being slotted at one side of said port, the bore of said closure putting the top and bottom of the cylinder into communication, the effective cross-sectional areas of the top and bottom of the closure, as exposed in said cylinder, being substantially equal, and means for moving the closure from port-closing position.

10. In a well cleaner adapted to be lowered through a well-casing, a body member having a low-pressure chamber and an inlet therefor, a closure embodying a member mounted for movement longitudinally of the body to and from a position closing the inlet, a sleeve mounted on the body member and movable longitudinally therewith, an operative connection between the sleeve and said closure whereby sleeve-movement in one direction is adapted to move the closure from the inlet, and a packer on the movable sleeve and adapted to engage the well-casing.

11. In a well cleaner adapted to be lowered through a well-casing, a body member having a low-pressure chamber and an inlet therefor, a closure embodying a member mounted for movement longitudinally of the body to and from a position closing the inlet, the body member having an inlet duct in communication with well-fluid and leading to the inlet closure, a sleeve mounted on the body member and movable longitudinally therewith, an operative connection between the sleeve and said closure whereby sleeve-movement in one direction is adapted to move the closure from the inlet, and a packer on the movable sleeve and adapted to engage the well-casing, there being by-pass ports in the body member above and below the packer and opening to said duct, said sleeve closing one of said by-pass ports when it is moved to open the closure.

12. In a well cleaner adapted to be lowered through a well-casing, a body member having

a low-pressure chamber and an inlet therefor, a closure embodying a member mounted for movement longitudinally of the body to and from a position closing the inlet, a sleeve mounted on the body member and movable longitudinally therewith, an operative connection between the sleeve and said closure whereby sleeve-movement in one direction is adapted to move the closure from the inlet, and a packer on the movable sleeve and adapted to engage the well-casing, there being a by-pass through the body member around the packer, said by-pass being closed when the closure is moved from the inlet, said sleeve opening the by-pass upon continued movement of the sleeve in a closure-opening direction.

13. In a well cleaner, a body member having a low-pressure chamber, a cylinder disposed in the lower end of the chamber, said cylinder being closed at its upper end and open at its lower end for admission of well-fluid, a side port through the wall of the cylinder and in communication with the chamber, a tubular closure mounted for movement in the cylinder to and from a position closing said port, the wall of said tubular closure being slotted at opposite sides of said port, the bore of said closure putting the top and bottom of the cylinder into communication, the effective cross-sectional areas of the top and bottom of the closure, as exposed in said cylinder, being substantially equal, and means for moving the closure from port-closing position.

14. In a well cleaner, a body member having a low-pressure chamber and an inlet therefor, a closure embodying a member mounted for movement to and from a position closing the inlet and having its bottom adapted to be exposed to well-fluid, there being a passageway interiorly of the body member adapted to conduct well fluid from beneath the closure to the top thereof, said top and bottom having substantially equal effective cross-sectional areas, a spring yieldably holding the closure in inlet-closing position, and means for moving the closure from inlet-closing position.

15. In a well cleaner adapted to be lowered in a well casing, a body member having a low-pressure chamber and an inlet therefor, a valve for said inlet, a packer adapted to engage the well casing and mounted for movement longitudinally of the body member, and an operative connection between the packer and valve whereby packer-movement relative to the body member is adapted to operate said valve, a spring yieldably holding the valve in inlet-closing position and yieldably holding the packer and body in predetermined relative positions, and means for setting up such relative movement by virtue of withdrawal movement of the cleaner.

16. In a well cleaner adapted to be lowered in a well casing, a body member having a low-pressure chamber and an inlet therefor, a tubular valve for said inlet, a packer adapted to engage the well casing and mounted for movement longitudinally of the body member, and an operative connection between the packer and valve whereby packer-movement relative to the body member is adapted to operate said valve, said connection including a tubular member attached to the valve and with its bore in communication with the valve bore, and means for setting up such relative movement by virtue of withdrawal movement of the cleaner.

JAMES J. SANTIAGO.
